DYNAMOELECTRIC MACHINE

Richard W. Dochtermen, Fort Wayne, Ind., assignor to
General Electric Company

Filed May 24, 1971, Ser. No. 146,597

Term of patent 14 years

Int. Cl. D13—01

U.S. Cl. D26—5

FIG.1

FIG.2

FIG.3

FIG. 1 is a perspective view of a dynamoelectric machine showing my new design;

FIG. 2 is a side elevational view of the dynamoelectric machine of FIG. 1; and

FIG. 3 is an end elevational view, somewhat enlarged, as seen from the bottom of FIG. 1.

I claim:

The ornamental design for a dynamoelectric machine, substantially as shown.
